DEVICE FOR USE IN THE ATTACHMENT OF
RUBBER HEELS TO SHOES

Joseph Coggans, Langside, Glasgow, Scotland

Application January 21, 1936, Serial No. 60,021
In Great Britain February 14, 1935

1 Claim. (Cl. 36—36)

The subject of this invention is a holder for attachment of rubber heels to shoes which is designed to permit removal and replenishment of such rubber heels without the use of tools.

- 5 A holder according to the invention comprises a metallic plate associated with means for attachment to the leather heel of the shoe to be fitted and provided with a peripheral flange defining a cavity adapted loosely to fit the associated rubber heel when the rubber heel is in a buckled state and closely to fit the rubber heel when the rubber heel is in a flattened state and having inturned jaw-forming serrations adapted lightly to engage the lateral walls of the rubber heel when the rubber heel is inserted in the cavity in a buckled state and forcibly to enter the lateral walls of the rubber heel when the rubber heel is flattened by pressure of the heel on the ground under the weight of the wearer.
- 10 15 20 25 30 35
- 10 A holder according to the invention comprises a metallic plate associated with means for attachment to the leather heel of the shoe to be fitted and provided with a peripheral flange defining a cavity adapted loosely to fit the associated rubber heel when the rubber heel is in a buckled state and closely to fit the rubber heel when the rubber heel is in a flattened state and having inturned jaw-forming serrations adapted lightly to engage the lateral walls of the rubber heel when the rubber heel is inserted in the cavity in a buckled state and forcibly to enter the lateral walls of the rubber heel when the rubber heel is flattened by pressure of the heel on the ground under the weight of the wearer.
- 15 20 25 30 35
- 15 A holder according to the invention comprises a metallic plate associated with means for attachment to the leather heel of the shoe to be fitted and provided with a peripheral flange defining a cavity adapted loosely to fit the associated rubber heel when the rubber heel is in a buckled state and closely to fit the rubber heel when the rubber heel is in a flattened state and having inturned jaw-forming serrations adapted lightly to engage the lateral walls of the rubber heel when the rubber heel is inserted in the cavity in a buckled state and forcibly to enter the lateral walls of the rubber heel when the rubber heel is flattened by pressure of the heel on the ground under the weight of the wearer.
- 20 25 30 35
- 20 An attachment constructed in accordance with the invention is illustrated in the accompanying drawing in which Fig. 1 is an inverted plan, Fig. 2 a section on the line 2—2 of Fig. 1, and Fig. 3 a section on the line 3—3 of Fig. 1, showing the rubber heel in a buckled condition. Figs. 4 and 5 are sectional views similar to Figs. 2 and 3 showing the heel in a flattened condition, a leather heel and part of the associated shoe being illustrated in Fig. 5.
- 25 30 35
- 25 Referring to the drawing, 1 denotes a shoe provided with a leather heel 2, and 3 denotes a rubber heel-holder attachable to the leather heel by means of screws 4 penetrating apertures 4' in the holder.
- 30 35
- 30 The holder is constituted by a metallic plate provided with a peripheral flange 5 defining a cavity 6 adapted loosely to fit the associated rubber heel 7 when the heel 7 is in a buckled
- state as shown in Figs. 2 and 3 and closely to fit the rubber heel when the rubber heel is in a flattened state as shown in Figs. 4 and 5. The flange 5 has inturned jaw-forming serrations 8 adapted lightly to engage the lateral walls 9 of the heel 7 when the heel 7 is inserted in the cavity in a buckled state as shown in Figs. 2 and 3, and forcibly to enter the lateral walls of the heel 7 when the heel 7 is flattened by pressure of the heel on the ground under the weight of the wearer.
- 35 40 45 50 55 60 65 70 75 80 85 90 95 100
- 35 In practice, the heel 7 is manipulated by the fingers so as to assume the buckled condition shown in Figs. 2 and 3, and is pressed into the cavity 6. When the heel 7 is released the lateral walls 9 are impaled on the serrations 8 as the heel 7 tends to assume a flattened condition due to the resiliency of the rubber. When the shoe 1 is fitted to the wearer's foot and the weight of the wearer is applied to the shoe with the heel 7 resting on the ground, the heel 7 is flattened and the serrations 8 are caused to bite into the walls 9.
- 40 45 50 55 60 65 70 75 80 85 90 95 100
- 40 To facilitate insertion of the heel 7 into the cavity and removal of the heel therefrom the line of serrations is interrupted near the inner edge of the holder 3 as indicated at 10.
- 45 50 55 60 65 70 75 80 85 90 95 100
- 45 I claim:
- 45 50 55 60 65 70 75 80 85 90 95 100
- 45 For a shoe provided with a leather heel, a holder for attachment of a rubber heel to said leather heel comprising a metallic plate associated with means for attachment to said heel and provided with a flange around its edge and breast portions, said flange having a plain portion adjacent the breast portion and having closely spaced inturned rigid projections along the remainder of the flange, said plain portion facilitating the attachment and removal of said rubber heel.
- 50 55 60 65 70 75 80 85 90 95 100

JOSEPH COGGANS.
